AERIAL TOY

Kurt R. Johmann and Frank T. Johmann, both of
49 Hampton Drive, Berkeley Heights, N.J.

Filed Feb. 25, 1964, Ser. No. 78,776

Term of patent 14 years

(Cl. D34—15)

FIGURE 1 is a side view of the aerial toy showing our new design, the view of the opposite side being the same.

FIGURE 2 is a top plan view on a reduced scale of the aerial toy.

FIGURE 3 is a rear elevational view on the scale of FIGURE 2 of the aerial toy.

FIGURE 4 is a front view of the toy of FIGURE 1 on the same scale as FIGURE 1.

FIGURE 5 is a cross-sectional view taken along the lines 5-5 of FIGURE 1.

We claim:

The ornamental design for an aerial toy, as shown and described.
